CLAIM

The ornamental design for an automobile control panel, as shown and described.

DESCRIPTION

FIG. 1 is a front elevational view of an automobile control panel showing our new design, the rear view being plain and need not be considered;

FIG. 2 is a top, plan view thereof, the bottom view being plain and need not be considered;

FIG. 3 is a left side elevational view thereof;

FIG. 4 is a right side elevational view thereof;

FIG. 5 is a top, front, left side perspective view thereof;

FIG. 6 is a top, front, right side perspective view thereof;

FIG. 7 is a top, plan view thereof, shown mounted in an automobile;

FIG. 8 is a top, front, left side perspective view thereof, shown mounted in an automobile;

FIG. 9 is a top, front, right side perspective view thereof, shown mounted in an automobile; and,

FIG. 10 is a top, rear, left side perspective view thereof, shown mounted in an automobile.

In the drawings, the broken lines in the figures depict portions of the article that form no part of the claimed design.
